UNITED STATES PATENT OFFICE.

GEORGE F. MATTESON, OF ROCKYHILL, CONNECTICUT, ASSIGNOR TO THE F. B. SHUSTER COMPANY, OF NEW HAVEN, CONNECTICUT, A CORPORATION OF CONNECTICUT.

WIRE STRAIGHTENING AND BURNISHING ARBOR.

Application filed January 18, 1927. Serial No. 161,746.

My invention relates to the class of machines used for straightening wire preparatory to various manufacturing operations thereon, and an object of my invention, among others, is the provision of a device of this kind in which the friction of the straightening elements on the wire shall be reduced to a minimum; and a further object of the invention is to provide a device of this class in which the straightening elements shall also act as burnishing elements; and a still further object of the invention is to provide a device that shall have a maximum of efficiency in operation and that shall be exceedingly simple in construction.

One form of device embodying my invention and in the construction and use of which the objects herein set out, as well as others, may be attained, is illustrated in the accompanying drawings, in which—

Figure 1 is a side view of my improved arbor.

Figure 2 is a similar view looking at the arbor from a point located at right angles to the point of view of Figure 1.

Figure 3 is an end view.

Figure 4 is a detail view, scale enlarged, of a portion of my improved arbor illustrating its construction, the top roller at the left being removed.

Figure 5 is a view in section on a plane denoted by the dotted line 5—5 of Figure 4.

Figure 6 is a detail end view of one of the plugs on enlarged scale.

Figure 7 is a detail view of one of the plugs with the end broken away in central section to show construction.

Figure 8 is a detail view illustrating the relative positions of the members of the pairs of rollers and on a plane denoted by the dotted line 8—8 of Figure 4.

Figure 9 is a detail view illustrating a little different means from that shown in Figure 4 for holding the plugs in place and for adjusting their positions axially.

Figures 10, 11, 12 and 13 are detail views illustrating different forms of the rollers.

In the accompanying drawings the numeral 15 indicates the body of my improved arbor that may be of ordinary form and construction and embodying a shaft 16 comprising a journal at one end and a shaft 17 comprising a journal at the opposite end, this latter shaft having a pinion 18 as a means for rotating the arbor. Means for support-

ing the arbor are not shown herein as these will be readily understood by those skilled in the art.

A series of holes 19 extend through the arbor, these holes being located preferably at equal distances apart to receive plugs 20 that are disposed in pairs, one pair in each of said holes and on opposite sides of an opening 14 extending lengthwise through the body and as shown in Figure 5 of the drawings. These plugs are all of similar construction and a description of one, therefore, answers for all.

Each plug has an adjusting screw 21 freely rotatable thereon but held against independent movement lengthwise thereof, said screw having a slot 22 for the reception of a screw driver as a means for adjusting the position of the plug. A notch 23 is formed in the end of each plug for the reception of rollers to be hereinafter described. These plugs, as hereinbefore stated, are located in pairs, one pair in each of the holes 19, said plugs being arranged with the notched ends toward each other, and these ends may be in contact.

In the form of the structure shown in Figures 4 and 5 each plug is cut away to provide a flat surface 24 to receive a holding pin 25 that is inserted through a hole 26 extending preferably in a diagonal direction through the arbor, and as shown in Figure 4 of the drawings.

In that form of the device shown in Figure 9 adjusting screws 27 are employed for the purpose of retaining the plugs against rotation, these screws abutting with their inner ends against flattened portions on the plug, and said screws being located on opposite sides of a plane passing diametrically through the plug so that the angular adjustment of the plug in the body 15 may be obtained.

A roller is rotatably mounted in each of the notches 23 so that a pair of said rollers are located in cooperating positions in each of the holes 19. These rollers may be embodied in different forms, but in each case there will preferably be a groove for the reception of the wire to be straightened, and these rollers will preferably be arranged in angular positions as hereinbefore referred to and preferably the angle of disposition of each pair of rollers being opposite to the pairs on one or both sides thereof, and as best shown in Figure 4 of the drawings.

In that form of the roller shown especially in Figures 4 and 6 each roller is composed of two members 28 of duplicate form and shaped to provide a groove 29 between them and in the roller as a whole. Each member is supported upon a ball bearing 30, as especially shown in Figure 7, and a spacing ball bearing 31 is located between the members of each pair of rollers. Balls 31 are located in recesses in the contiguous faces of the roller members, and the balls 30 are located in similar recesses formed in the outer sides of the roller members and in the contiguous ends of ball bearing plugs 32 located in holes extending through branches 33 created by the notches 23 in the ends of the plugs 20. These ball bearing plugs are threaded to fit the threaded walls of the holes in which they are located and they may be provided with notches to receive a screw driver as a means for adjusting them.

It will be seen, as shown in Figure 7, that the roller members of each pair of rollers may have a tipping action relative one to the other, so that they will readily adjust themselves to any inequalities in the wires being straightened. The plugs 32 may be secured in place as by set screws 34.

The structures shown in Figures 10 to 13 are very similar to those shown in the preceding figures and hereinbefore described, the differences being principally in the shape of the roller members, said members 35 in the structure of Figure 10 having a straight bevel and the members 36 in Figure 13 having a convex sloping surface, especially adapted for operation upon a wire 37 of an angular shape in cross section.

In the structure shown in Figure 11 the roller member 38 has conical bearings 39 to receive a pin 40 with a conical end and a screw 41 with a conical end. A sleeve 42 is employed for holding the pin in place. With this construction the pin may be duplicated on the opposite side and the same is true of the screw.

In that form of the device shown in Figure 12 the roller member 43 is of a single piece, as in Figure 11, and it is supported at opposite sides upon balls 44 that are held in place in recesses in branches of the plug 20 as by a sleeve 45 in a manner similar to the structure shown in Figure 11.

It will be noted that the pairs of plugs in each of the holes 19 may be adjustably positioned laterally of the body 15, and it will be found that if this adjustment of the several plugs is so made that the entire set of plugs will assume a curved or arched form with the highest point of the arch at about the lengthwise center of the body, as shown in Figure 2, extremely satisfactory results will be obtained.

The construction of the plugs and the roller members as illustrated and described herein

enables the device to be used not only as a wire straightener, but also as wire burnisher, it having been found that the wire when delivered from the structure will be nicely burnished, and in accomplishing this result 70 I time the rate of rotation of the body and the rate of travel of the wire through the straightener in such ratio that succeeding sets of roller members 28 will make contact with the wire in different helical lines from 75 that traveled by preceding sets of roller members so that substantially the entire surface of the wire will be acted upon by the roller members, and so far as appearance is concerned the entire surface of the wire will be 80 thus burnished.

In straighteners heretofore employed and comprising straightening elements having a purely rubbing contact with the wire, as the body is rotated and as the wire travels 85 through the body, much difficulty has been encountered by reason of the great friction that tends to rotate the wire which, however, must be held against rotation and special means are therefore required to prevent such 90 rotation of the wire. This is especially true at the time the end of the wire passes from the reel upon which it is wound, which owing to the curved form of the wire caused by its winding upon the reel, will having a whipping or gyratory motion imparted to it if rotation takes place, and even at other times this friction may cause the wire to be twisted off.

By the use of the roller straightening and 100 burnishing members herein illustrated and described this friction is reduced to a minimum and to such extent that the tendency of the wire to rotate is practically eliminated and the ordinary feed rolls will be found sufficient to prevent the wire from rotating and 105 no special device will, therefore, be required for this purpose.

The axis of each of the rollers is inclined 110 in such direction that both travel of the wire through the body and rotation of the body about the wire is aided, and the degree of this angle will be such as to secure these results. That is, the axes are so inclined that revolution of the rollers around the wire will cause 115 rotation of the rollers in a direction to aid in the results obtained, that is, movement of the wire is impeded to a minimum degree, the rollers rotating in a direction naturally caused by such rotation.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim—

1. A wire straightener including a body having an opening extending lengthwise therein and a hole intersecting said opening on opposite sides thereof, a pair of plugs located in said hole in a line diametrically through said body, and a pair of rollers rotatably mounted in said plugs to receive a wire between them. 65
2. A wire straightener including a body having an opening extending lengthwise therein and a hole intersecting said opening, a screw threaded plug fitting a screw threaded wall of said hole, and a roller rotatably mounted in and carried by said plug. 70
3. A wire straightener including a body having an opening extending lengthwise therein and a set of holes intersecting said opening on opposite sides thereof, a pair of plugs located in each of said holes on diametrically opposite sides of the body, and rollers rotatably mounted in each of said plugs. 75
4. A wire straightener including a body having an opening extending lengthwise therein to receive a wire and a hole intersecting said opening, a plug rotatably mounted in said hole, a roller rotatably mounted in said plug, and means for positioning said plug so that the axis of said roller will be located diagonally to the path of travel of a wire through said opening. 80
5. A wire straightener including a body having an opening extending lengthwise therein to receive a wire and a hole intersecting said opening, a pair of plugs located in said hole on opposite sides of the path of travel of a wire through said opening, a roller rotatably supported by each of said plugs, and means for positioning said plugs so that the axis of both of said rollers will be inclined in opposite directions with respect to the path of travel of a wire through said opening. 85
6. A wire straightener including a body having an opening extending lengthwise therein to receive a wire and a plurality of holes intersecting said opening, a plurality of rollers, and a plug for rotatably supporting each of said rollers, said plugs being positioned with the axis of each roller extending diagonally in a different direction from that of other of said rollers. 90
7. A wire straightener including a body having an opening extending lengthwise therein to receive a wire and a plurality of holes intersecting said opening, a plurality of rollers, and a plug for rotatably supporting each of said rollers, said plugs being positioned to locate the axis of each roller to extend diagonally in a different direction from that of the roller next thereto. 95
8. A wire straightener including a body having an opening extending lengthwise therein to receive a wire and a plurality of holes intersecting said opening and extend- 100
- ing thereacross, a pair of plugs located in each of said openings, a roller rotatably mounted in each of said plugs, and means for positioning said plugs so that the axes of the rollers in each pair of plugs will extend in different directions diagonally across the path of travel of a wire through said opening, and said axes of each pair of rollers will extend in opposite directions to that of corresponding rollers of other pairs of rollers. 105
9. A wire straightener including a body having an opening extending lengthwise therein and a hole intersecting said opening, a plug located in said hole, engaging the wall thereof, and projecting beyond the end thereof, means for rotatably adjusting said plug, and a roller rotatably mounted and carried by the projecting end of said plug to contact with a wire traveling along said opening. 110
10. A device for operating upon a wire and including a body having an opening extending lengthwise therein, a roller support, and roller members comprising two parts rotatably mounted in said support, and means for permitting movement of the members of said roller one with respect to the other. 115
11. A device for operating upon a wire and including a body having an opening extending lengthwise therein, a roller support, a roller rotatably mounted in said support to engage a wire traveling along said opening, and a ball located in a recess in each side of said roller and in a recess in said support to rotatably support said roller. 120
12. A device for operating upon a wire and including a body having an opening extending lengthwise therein, and roller members comprising two parts rotatably mounted in said support to engage a wire traveling along said opening, and a ball located in a recess in the adjacent faces of said roller members. 125
13. A device for operating upon wire and including a body having an opening extending lengthwise therein, a roller support, a two part roller rotatably mounted in said support, a ball located in a recess in each of said roller members and in a recess in said support, and a ball located in recesses in the adjacent faces of said roller members. 130
14. A wire straightener including a body having an opening extending lengthwise therein to receive a wire and a hole intersecting said opening, a plug located in said hole, a roller rotatably mounted in said plug, and means for positioning said plug so that the axis of said roller will be located diagonally to the path of travel of a wire through said opening and at such angle as to least impede the travel of wire along said opening. 135
15. A roller support, a two-part roller rotatably mounted in said support, and a ball located between said roller members and on the axial center thereof. 140

16. A roller support, a two-part roller rotatably mounted in said support and having means for permitting relative movement of said roller members, a ball located on each side of said roller member and between it and a recess in said support, said balls being located on the axial center of said roller member.
17. A roller support, a two-part roller rotatably mounted in said support, a ball located between said roller members on the axial center thereof, and a ball located at each end of said roller member and between it and said support and on the axial center of said roller member. 10

GEORGE F. MATTESON.
